PRESSING MACHINE AND MAINTAINING MEANS

Filed July 18, 1934

FIG. 2

UNITED STATES PATENT OFFICE

2,043,480

PRESSING MACHINE AND MAINTAINING
MEANS

George W. Johnson, Cincinnati, Ohio, assignor to
The American Laundry Machinery Company,
Norwood, Ohio, a corporation of Ohio

Application July 18, 1934, Serial No. 735,801

7 Claims.

(Cl. 68—9)

This invention relates to a pressing machine of the type used in laundry and garment work and more particularly to a machine in which the pressing members have a marked degree of curvature. That is to say, the invention is addressed to the performing of pressing operations in two directions simultaneously for the purpose of pressing or ironing articles, such as men's shirts wherein portions of the pressing members coact

5 to iron the front or back of the shirt, while other portions of the pressing members cooperate to iron certain of the side portions of the shirt.

An object of this invention is to provide in a machine of the general type described, cooperating 10 pressing members each having a central pressing portion and a side pressing portion extending at an angle thereto, one of the members being provided with a cover member or flexible bag enclosing the side portion thereof and expandable by fluid pressure against the coacting side portion of the other member when the members are in pressing position. The coacting side portions are so constructed that the cover member is extended by fluid pressure means into a 15 locking engagement with the coacting member so as to serve as a maintaining means after the press is closed.

A further object of the invention is to provide a pair of coacting pressing members having side 20 pressing portions and having a part on the side portion of one member adapted to lockingly engage a part on the side portion of the other member, together with means actuated automatically upon movement of the members into pressure 25 engagement for lockingly engaging the parts.

Other objects and advantages of my invention, including means for opening and closing the press and control mechanism therefor, will appear from the following description when taken with the 30 drawing, in which Fig. 1 is a side elevation partly in section and partly diagrammatic, showing a pressing machine embodying my invention, the parts are shown in press open position in full lines, and with the parts in pressing position 35 but before the bag member is inflated in dot-dash lines; Fig. 2 is an enlarged fragmental sectional view of the head and bed, showing the bag member inflated to produce ironing pressure; while Fig. 3 is an enlarged fragmental view of 40 certain of the valve mechanism in Fig. 1, showing the parts in operated position.

I have illustrated my invention as applied to a press of the scissors type comprising a frame 45 on which is mounted a pedestal 11 carrying a bed member 12. An upstanding bracket 13 on

the frame pivotally supports a head lever 14 on which is mounted a head member 15 adapted to coact with the bed 12. The head lever and therefore the head member itself is moved into pressing position, which is the position indicated in 5 dot-dash lines in Fig. 1, by means of toggles 16 and 17 in operative position between the frame and the rear end of the head lever.

For moving the toggles toward straightened position, I have provided a cylinder and piston 10 motor 18 pivotally mounted on the frame by trunnions 19 and which is provided with a piston 20 connected by means of a piston rod 21 with the toggle mechanism. For the control of pressure fluid flow to and from the motor, I have 15 illustrated a conventional two-hand control mechanism comprising a normally closed intake valve 22 and a combined normally closed intake valve 23 and normally open exhaust valve 24. These latter valves are mounted on a common 20 stem 25 operable by control member 26, and valve 22 is likewise operable by a control member 27. Pressure fluid is supplied upon depression of both control members by way of conduit 28, valve 22, conduit 29, valve 23 and conduit 25 30 to the forward end of the motor cylinder. This moves piston 20 rearwardly, which in turn straightens the toggle mechanism to the dot-dash position of Fig. 1 where the pressing members are in position to coact upon inflation of 35 the cover member of the bed.

The bed construction is best seen in Fig. 2 where the bed comprises a central portion 31 having depending side portions 32 extending at an angle to the central portion. A flexible cover 35 member or bag 33 encloses the central and side portions of the bed and has a fluid-tight connection therewith, that illustrated comprising a bar 34 secured to the bed casting by screws 35. The cover or bag member thus forms a fluid-tight 40 chamber 36 completely surrounding the pressing surfaces of the bed member. The cover member 33 is of a slightly expandible or extensible material substantially impervious to the operating fluid and preferably formed of plies of 45 impregnated fabric.

The head member comprises a central portion 37 and downwardly extending side portions 38 which are adapted to coact with the side pressing portions of the bed member so as to cause a 50 pressing action at a substantial angle to the pressing action provided between the central portions 31 and 37.

After the pressing members reach the dot-dash 55 position of Fig. 1, means is provided for supply-

ing fluid under pressure to the chamber 36 so as to expand the bag or cover member 33 for causing the ironing or pressing action between the coacting members. The means illustrated 5 comprises mechanism actuated automatically upon movement of the pressing members into their pressing position. As illustrated, a valve casing 39 is mounted on the frame and encloses a normally closed inlet valve 40 and a normally 10 open exhaust valve 41 which are maintained in their normal position by a spring 42. Pressure fluid inlet to the valve casing is by way of conduit 43 and exhaust therefrom is by way of conduit 44. A common inlet and exhaust conduit 15 45 communicates between the valve casing and chamber 36 of the bed. Valves 40 and 41 are mounted on a common stem 46 which is operable by a bell crank lever 47 which has a connection with the operating mechanism of the press so 20 that valves 40 and 41 may be operated automatically upon movement of the pressing members to their pressing position. The connection illustrated comprises a link 48 pivotally mounted on toggle member 17 and adapted to contact the 25 vertical arm of lever 47 just before the parts reach the dot-dash position of Fig. 1. The link is adapted to yieldingly operate the lever 47 by mounting on the end of the link a spring 49 held thereon by adjustable retaining means 50.

30 The operation of this portion of the mechanism is as follows: Valve 40 being normally closed and valve 41 open, the pressure chamber 36 is normally in exhausted or slack condition by way of conduit 45, valve 41 and conduit 44 communicating with the atmosphere. Upon movement of the parts to the dot-dash position of Fig. 1, valve 41 is closed, valve 40 is opened and pressure fluid is supplied to the pressure chamber 36 which distends the cover member 33 to the position of 40 Fig. 2. At the close of a pressing operation, bell crank lever 47 is oscillated in a counter-clockwise direction against the yielding spring 49 by operator operated means comprising a pedal 51 pivoted to the frame and connected by 45 link 52, bell crank 53 and link 54 with the bell crank lever 47. Pressure on pedal 51 moves lever 47 to the full line position of Fig. 1, which permits spring 42 to return the valves to their normal position, thus exhausting the pressure 50 chamber 36.

The pressing members are so constructed that upon their movement into final pressure engagement a part of the side pressing portion of one member so enters a part of the side pressing 55 portion of the other member as to lock the members in their engaged position. This arrangement permits the operator to release the control members 26 and 27 as soon as the press is completely closed and in pressure engagement. In 60 the arrangement illustrated, the depending side portions 38 of the head are inclined toward the longitudinal vertical medial plane of the bed, so that when the cover member 33 is distended a portion of the cover member extends into locking 65 engagement with the side portion of the other member. As seen in Fig. 2, the distance between the lowermost portions of opposed side portions 38 on the head is sufficient to permit the head to move downwardly and enclose the bed when the cover 33 is deflated. But the said 70 distance is less than the overall dimension of the bed and cover when the latter is distended. A spring 55 connected between the rear end of the head lever and the frame normally tends to 75 open the press, but is ineffective to do so when

the cover is distended into locking engagement with the side pressing portions of the head.

Thus, when final pressure has been applied by distending the cover, following actuation of the valves in casing 39, the parts will remain in that 5 position until the operator depresses lever 51. Therefore the operator is free to release control members 26 and 27 as soon as the press is closed, whereupon pressure fluid is exhausted from motor 18 through conduit 30 and exhaust valve 34. 10

It is apparent that the control valves for cover inflation, once operated into cover-distending position, are self-maintained in that position until pressure is applied to lever 51, and this maintaining action is entirely independent of the mo- 15 tor 18.

What I claim is:

1. In a press of the class described, the combination of a pair of coacting head and bed pressing members each having a central pressing portion and depending side pressing portions, means for causing relative approach of said members into pressing position, the depending side pressing portions of said head member being inclined toward the longitudinal vertical medial plane of 25 said bed member, a flexible cover member secured to said bed member and enclosing said side pressing portions thereof, and fluid pressure means operable when said pressing members are in pressing position to distend said cover member 30 into engagement with the side pressing portions of said head member, whereby when said cover member is distended the pressing members will be locked together.

2. In a press of the class described, the combination of a pair of coacting pressing members each having a central pressing portion and depending side pressing portions, a flexible cover member forming a fluid-tight casing enclosing the side portions of one of said members, means 40 for causing relative approach of said members into pressing position, fluid pressure means operable when said pressing members are in pressing position to distend said cover member into engagement with the side pressing portions of the 45 other member, means tending at all times to separate said pressing members and to open the press, and said distended cover member and said engaged side pressing portions of the coacting pressing member interlocking to prevent operation of said press-opening means.

3. In a press of the class described, the combination of a pair of coacting pressing members each having a central pressing portion and a side pressing portion extending at an angle 55 thereto, means for causing relative approach of said members into pressing position, means tending to separate said members, a cover member enclosing the side portion of one of said members, fluid pressure means operable when the 60 pressing members are in pressing position to distend said cover member into engagement with the side portion of the coacting pressing member, and portions of said cover member in distended position extending into the side portion of said 65 last-named coacting pressing member.

4. In a press of the class described, the combination of a pair of coacting pressing members, each having a central pressing portion and a side portion extending at an angle thereto, means 70 for causing relative approach and pressure engagement between said members, and fluid pressure actuated means on the side portion of one member and adapted to lockingly enter into the side portion of the other member when the mem- 75

bers are in pressing position, to prevent disengagement of said members.

5. In a press of the class described, the combination of a pair of coacting pressing members each having a central pressing portion and a side portion extending at an angle thereto, means for causing relative approach and pressure engagement between said members, a part on the side portion of one member adapted to lockingly 10 enter into the side portion of the other member to prevent disengagement of said members, and means actuated automatically upon movement of said members into pressure engagement for lockingly engaging said parts.
- 15 6. In a press of the class described, the combination of a pair of coacting pressing members one of which is movable into and out of position adjacent the other, one of said members having a flexible cover substantially enclosing the pressing surface thereof in a fluid-tight construction, fluid pressure means operable when said pressing members are in adjacent position to distend 20 said cover away from its associated member,

means for moving said movable member to place said members in adjacent position, and means independent of said last-named means for locking said members in said position.

7. In a press of the class described, the combination of a pair of coacting pressing members one of which is movable into and out of position adjacent the other, means for so moving the movable member, one of said members having a flexible cover substantially enclosing the pressing surface thereof to form a fluid-tight chamber, fluid pressure means operable when said pressing members are in adjacent position to distend said cover into engagement with the coacting member, control means for said fluid pressure means and operable in cover-distending direction when said members move into adjacent position, and said distended cover member having parts distended into interlocking relation with the coacting pressing member for preventing disengagement of said pressing members.

GEORGE W. JOHNSON.
